UNITED STATES PATENT OFFICE.

FRANK E. PHILLIPS, OF WELLS, MAINE.

TELEPHONE-SIGNAL-OPERATING DEVICE.

1,170,323.

Specification of Letters Patent.

Patented Feb. 1, 1916.

Application filed November 12, 1912. Serial No. 730,835.

To all whom it may concern:

Be it known that I, FRANK E. PHILLIPS, a citizen of the United States, residing at Wells, in the county of York and State of Maine, have invented new and useful Improvements in Telephone-Signal-Operating Devices, of which the following is a specification.

My present invention relates to telephone signals, and more particularly to means comprising an electric light disposed adjacent the telephone apparatus, such as at the exterior of the telephone booth, which will be automatically placed in circuit with a suitable source of electric energy, as soon as the receiver is raised from the hook of the telephone apparatus.

The principal object of my invention is to provide signal apparatus which may be placed into operative relation with existing telephone apparatus to provide a signal whereby, when the telephone apparatus is in service, a suitable signal will be displayed for the purpose of advising other parties desiring to use the telephone that the instrument is in service.

A further object of my invention is to embody in connection with the apparatus a circuit which will provide for the proper illumination of the signal, the wires of such circuit being remote from the telephone apparatus. This is in contradistinction to apparatus already disclosed to the public wherein the switching means for the electric signal is necessarily closely adjacent the receiver and transmitting mechanism.

Further objects of my invention will appear in the following detail description taken in connection with the accompanying drawings, forming a part of this specification.

In the drawings, the device of my invention is schematically illustrated in the proper circuit connection.

The numeral 10 designates an ordinary telephone apparatus which includes a transmitter 11, a bracket and shelf 12 and 13 respectively, and a receiver hook and receiver 20 and 21, respectively. The telephone apparatus is preferably of that type wherein the receiver hook is mounted on an arm, designated 19 in the drawing, and oscillatable about a pivot point 18. This arm co-acts with a contact 15 in conducting communication with the transmitter mechanism and it is to be noted that, when the receiver 21 is

held by a hook 20, the circuit is broken at arm 19 and contact 15.

The shelf 13 supports suitable batteries 14 placed in series as by wires 24, 25 and 26. One pole of the battery is in conducting communication with the receiver as through wire 23, while the other pole of said battery is in conducting communication with one of the line wires as through lead 27. The other pole of the receiver 21 is in conducting communication with the arm 19 as through wire 22. The transmitter is placed in conducting communication with the other line wire as through lead 17.

An electro-magnetic device interposed in the circuit of the receiver and transmitter such as by having conducting communication with the series connection wires 25 and 26, comprises a base portion 28 having a pair of standards 29 positioned thereon and secured in place through the medium of pins 30. These standards support an oscillatable arm 32, as through screws 31. The arm 32 is normally held in a predetermined position through the medium of a coil spring 33, said spring having connection with the eyelets 34 on the standards 28 and on arm 32, respectively.

An electro-magnet 35 is positioned upon the base plate 28 and for coaction with this electro-magnet is an armature 36 secured to the arm 32 as by screw 37. The amplitude of oscillation of the arm 32 is controlled by means of screws 42 and 43' carried by the extension 41 of a standard 39, secured to base 28 as by screw 40. It is to be noted that the spring 33 so acts upon arm 32 that it normally engages the set screw 42 and by manipulation of this set screw the arm can be so adjusted as to provide for successful operation of the electromagnet when energized to draw the armatures toward the core 38 of the electromagnet.

The base 28 also carries two switch points 43 insulated one from another, while the arm 32 carries a bridge piece 45, preferably triangular in shape, secured to the arm as by screw 46. It is to be noted that the switch points 43 are beveled as at 44 to accommodate this bridge piece and that when the electro-magnet 35 is energized and draws the armature 36 toward its core 38, the bridge piece 45 brings the switch point 43 into conducting communication.

The main line wires of an electric lighting circuit are designated by 49 and in commu-

nication with one of these wires, as through wire 51 is an electric light 50. This light is also in conducting communication with one of the switch points 43 as by wire 47. The other switch point 43 is in conducting communication with the other line wire 49 as through wire 48. It is to be understood that the line wires 49 carry a current of such voltage as to successfully illuminate the light 50 when a current is conducted therethrough.

When embodying apparatus constructed according to my invention in connection with existing telephone apparatus, it is merely necessary to place the electro-magnetic device in circuit with the receiver and transmitter, which circuit is controlled by action of the receiver hook,—the circuit being completed when the receiver hook is relieved of the weight of the transmitter. The electro-magnetic device may be disposed in close proximity to the telephone apparatus or remote therefrom as may be desired. It is also to be noted that the line wires 49 may be remote from the telephone apparatus and in this way, conductors carrying a current of high voltage are not placed in close proximity to the telephone apparatus.

The operation of the apparatus is as follows:—As disclosed in the drawing, the receiver is shown as having been removed from the hook and the receiver and transmitter circuit is completed. Inasmuch as the electro-magnet 35 is in circuit with the transmitter and receiver, it is energized and the armature 36 is drawn toward its core 38. This action brings the bridge piece 45 into contact with the switch points 43 and consequently a circuit is completed through light 50. Inasmuch as it is contemplated to display this light at such a point as to give notice to prospective users of the telephone, it will serve its purpose as a signal so long as the receiver remains off the hook 20. As soon as the receiver is replaced, the receiver and transmitter circuit is broken and conse-

quently the arm 32 is permitted to move responsive to spring 36 breaking the circuit of light 50.

Changes in detail may be made without departing from the spirit or scope of my invention; but,

I claim:—

1. In a signal system for telephones, the combination with a telephone apparatus including means for completing the receiver and transmitter circuit only when the apparatus is brought into use for audibly communicating, of an electric light, a light circuit, switch points connected in said light circuit and separated one from the other to form a gap in said circuit, and means connected in the receiver and transmitter circuit to become operative upon closing said receiver and transmitter circuit to bridge the switch points and thus complete the lamp circuit.

2. In a signal system for telephones, the combination of a telephone apparatus including means for completing the receiver and transmitter circuit only when the apparatus is brought into use for audibly communicating, an electromagnet disposed in the said receiver and transmitter circuit of said telephone apparatus, an armature for said electromagnet, a light circuit having a gap therein, switch points connected in said circuit at the gap and separated one from the other, a bridge piece connected with said armature adjacent the location of said switch points, and all of said parts so arranged that as the receiver and transmitter circuit is closed this current is passed through the electromagnet and the bridge piece is brought to a relation to contact across said switch points and complete the connection through the lamp circuit.

FRANK E. PHILLIPS.
